UNITED STATES PATENT OFFICE.

JOSEPH H. BOURGON, OF DETROIT, MICHIGAN, ASSIGNOR TO THE STUDEBAKER CORPORATION, OF SOUTH BEND, INDIANA, AND DETROIT, MICHIGAN, A CORPORATION OF NEW JERSEY.

TOP CONSTRUCTION.

Application filed November 4, 1924. Serial No. 747,847.

To all whom it may concern:

Be it known that I, JOSEPH H. BOURGON, a subject of George V, King of Great Britain and Ireland, and resident of Detroit, in the county of Wayne and State of Michigan, have invented certain new and useful Improvements in Top Constructions, of which the following is a specification.

This invention relates to vehicle top constructions, and particularly to tops for open types of automobiles provided with side enclosures movable vertically into the top when placing them in inoperative position, and is particularly applicable to open type tops provided with roller curtains, such as is described in my previous application filed July 9, 1924, Serial No. 725,062.

An object of the present invention is to provide an automobile top of the open type construction with top supports which are secured thereto, in such a manner that the whole structure forms a single unit attachable to the automobile as such.

Another object is to provide a top support with grooves for guiding the adjacent edge of the adjacent curtain when it is raised or lowered and for retaining it in such lowered position.

A further object is to provide an automobile top support formed from sheet metal into substantially a trough-shaped section, the free edges of the metal being bent and shaped in such a manner as to form a substantially T-shaped trough or groove in the rear face thereof, for receiving and guiding the edge of the adjacent curtain when it is being raised or lowered, and for retaining it in such lowered position.

A still further object is to provide the top support with reinforcements or stiffening members to give a more rigid structure.

Still another object is to provide the front top supports with means for securing the windshield and rainshield quadrants thereto.

The above being among the objects of the present invention the same consists of certain features of construction and combination of parts to be hereinafter described with reference to the accompanying drawings, and then claimed, having the above and other objects in view.

In the accompanying drawings which il-

lustrate a suitable embodiment of the present invention and in which like numerals refer to like parts throughout the several views,

Figure 1 is a fragmentary perspective view showing the location of the right front top support in respect to the top and the automobile body, also showing the windshield and rainshield quadrant attached thereto, and a portion of the adjacent curtain in a partly lowered position.

Figure 2 is a side view of the right front support, a portion being broken away to show the tapping block at the point of attachment of the windshield and rainshield quadrant.

Figure 3 is a fragmentary perspective view showing the method of securing the top support to the front top cross member.

Figure 4 is a fragmentary vertical sectional view taken through the left top support base showing the method of securing the support to the automobile body.

Figure 5 is a broken perspective view showing the position of the left front curtain in the left front top support.

Figure 6 is a fragmentary sectional view of one of the front top supports and co-operating curtain, taken in a plane perpendicular to the length of the support at a point corresponding to the broken end of the support shown in Figure 5, and showing the means employed to prevent the curtain from drawing out of the groove in the support.

Figure 7 is a plan view of the top of the support shown in Figure 2.

Figure 8 is a section of the support taken on the line 8—8 of Figure 2.

Figure 9 is a section of the support taken on the line 9—9 of Figure 2.

Figure 10 is a plan view of the face of the base of the support shown in Figure 2.

Referring to the numbered parts of the drawings, the top 20 may be of any conventional type having a suitable front cross member, such as 21, and is supported on each side of the automobile body 22 by a top support 23 positioned at the extreme front end of the top 20, which subsequently carries a small portion of the weight of the top but primarily acts to steady the front therefor and to guide the adjacent curtain

24 as will be described later. The rear portion of the top 20 may be supported in any manner found suitable, but supports therefor are preferably rigidly secured to the top 20 so that the top 20 and supports 23 form a single unit that may be attached to the body 22 as such.

Each support 23 is constructed mainly of sheet metal suitably reinforced, and is flared 10 outwardly towards each of the attaching surfaces. As clearly shown in Figures 7, 8 and 9, the sheet metal is shaped to a substantially troughlike section 25, the bottom of the trough being at the front of the support 15 23, the free edges being bent inwardly towards each other at substantially 90 degree angles to form the flat rear face of the support 23, and then bent inwardly towards the front of the support leaving an opening 26 20 in the rear face, and lastly formed to a rectangular shaped section or groove 27 within the first formed trough-like structure 25, which process of shaping of the free ends of the metal forms a substantially T-shaped 25 groove, whereby to receive the edge of the curtain 24. Buttons 28, secured at spaced intervals to that edge of the curtain 24 lying within the groove 27, are of a thickness greater than the width of the opening 26 30 and prevent the curtain 24 from pulling out of the groove 27, the curtain 24 having a plurality of buttons 28 secured thereto, and positioned within the T-shaped groove as clearly shown in Figures 5 and 6. A curved 35 lip 47 is formed in the sheet metal at the top of the support at one side of the T-shaped groove for guiding the curtain 24 into said T-shaped groove.

The top support 23 is secured to the body 40 22 at the edge of the cowl by bolts 29 which pass through the body brace 30 (see Figure 4) and the shroud bracket 31 and thread into openings 32 provided in the top support reinforcement or anchoring member 33, the openings 32 being more clearly shown in 45 Figure 10. The metal of the top support 23 is formed around the edges of the anchoring member 33 and is welded thereto as shown in Figures 4 and 10.

As the top supports 23 and the top 20 form a unit, the supports 23 are first assembled to the top 20 and the unit is assembled to the body 22 as such and if no other means were employed, it would be necessary to 50 have a person remain on each side of the body 22 to support and guide the top while the bolts 29 were being threaded into their respective openings 32 in the anchoring member 33, but to eliminate this work and to eliminate the time and effort involved in 55 centering the threaded openings 32 over the corresponding openings in the shroud bracket 31 and body brace 30 a dowel pin 34 is anchored in the shroud bracket 31 which, 60 when the top 20 is being positioned on the 65

body 22, extends up into an opening 35 provided in the anchoring member 33 and centers the openings 32 over the corresponding openings in the shroud bracket 31 and body brace 30, whereby the bolts 29 may be easily 70 threaded into their respective openings 32.

The support 23 is provided at its upper end with an apertured offset member or ear 75 36 formed therefrom or welded thereto and is secured to the angle 37 which acts to tie the front cross member 21 and the top side quarters together, by means of a bolt 38 which passes through the angle 37 and ear 36 on to which is threaded a nut (not shown).

As shown in Figure 1, the rainshield 39 and windshield 40, being hingedly mounted by suitable means on the front cross member 21, are adjustably positioned on a quadrant 41 which is secured to the flat surface 42 on said support 23, by means of screws 43 that thread into openings 44 provided in a tapping block 45, which is welded to the inside of the support 23 just back of the flat surface 42.

A reinforcing member 46 is positioned in the trough-like section 25 directly back of the front of the support and at a point directly above the anchoring member 33 and is welded to both the anchoring member 95 and the support 23, the purpose being to provide means to absorb the bending strains which are created by the weaving of the top 20 and are more evident at that point.

It will be evident that the construction described provides a simple, inexpensive yet strong support and readily adapts itself to tops of the permanent type using curtains which slide vertically up and down, and a support which does not materially obstruct 100 the view of the occupants of the automobile.

Formal changes may be made in the specific embodiment of the invention described without departing from the spirit and substance of the broad invention the scope of 110 which is commensurate with the appended claims.

What I claim is:—

1. In combination with an automobile top having a vertical movable side enclosure, of 115 a top support formed of sheet metal into a substantially trough-shaped section for receiving and guiding the adjacent edge of said enclosure, the free edges of said support entirely forming said trough-shaped 120 section and being concealed by the outer walls of said support.

2. In combination with a top for an automobile having a vertically movable side enclosure, of a top support formed of sheet 125 metal into a substantially trough shaped section the free edges of which are shaped to form a substantially T-shaped groove in cross section within said trough-shaped section for receiving and guiding the adjacent 130

edge of said enclosure, and the lower end of said support being flared outwardly to provide an enlarged attaching surface.

3. In combination with a top for an automobile having vertically movable side enclosures, of top supports formed of sheet metal into a substantially trough-shaped section the free edges of which are shaped to form a substantially T-shaped groove in cross section within said trough-shaped section for receiving and guiding the adjacent edges of said enclosures, said supports being flared outwardly at their ends, and means for securing said supports in operative positions.

4. In combination with a top for an automobile having vertically movable side enclosures, of top supports formed of sheet metal into a substantially trough-shaped section the free edges of which are shaped to form a substantially T-shaped groove in cross section within said trough-shaped section for receiving and guiding the adjacent edges of said enclosures, said supports having an upwardly projecting lip adjacent their upper end and at one side of said T-shaped groove for guiding the adjacent edges of said enclosures thereinto.

5. In combination with an automobile top having vertically movable side enclosures, of top supports formed of sheet metal into a substantially trough-shaped section, the free edges of which are shaped to form a substantially T-shaped groove in cross section within said trough-shaped section for receiving and guiding the adjacent edges of said enclosures, said supports having their upper ends flared outwardly to provide means for securing said top to said automobile and having an upwardly projecting lip for guiding the adjacent edges of said enclosures into said T-shaped groove.

6. In combination with a top for an automobile having a vertically movable side enclosure provided with buttons secured at spaced intervals to the edge thereof, of a top support formed from sheet metal to a substantially trough-shaped section, the free ends of which are bent inwardly towards each other, and then bent forwardly parallel to each other towards the front of said support to form a guide of less width than the thickness of said buttons, and lastly enlarged to a rectangular shaped section of sufficient width to receive said buttons, whereby the edge of said enclosure will be retained within said support.

7. A top support for vehicles formed from sheet metal, the free edges of the metal being bent to form a slot within the outer walls of said support, said slot being T-shaped

in cross section and the free edges of the metal being concealed by the outer walls of said support.

8. In combination with an automobile body having an attaching surface provided with a plurality of openings and an upwardly projecting dowel pin, a plurality of bolts adapted to extend through said openings, a support formed from sheet metal to a substantially trough-shaped section and having a T-shaped groove in cross section formed within said trough-shaped section by the free edges of the metal of said support, and a reinforcing member positioned in the base of said support having the bottom edges of the metal bent therearound and secured thereto, said reinforcing member having threaded openings therein into which said bolts are threaded for securing said support to said automobile body, and having an opening therein for receiving said dowel pin whereby said threaded openings may be brought into matching relation with said openings in said surface.

9. In an automobile top support formed from sheet metal to a substantially trough-shaped section and having a T-shaped groove in cross section formed within said trough-shaped section by the free edges thereof, a reinforcing anchoring member at the base of said support having the bottom edge of the metal of said support bent therearound and secured thereto, and a reinforcing member positioned within said trough-shaped section and extending upwardly from said anchoring member, said reinforcing member being secured to both said anchoring member and said support to absorb the bending strain created by the weaving of the automobile top.

10. In combination with an automobile having a top and a vertically movable enclosure provided with protuberances along an edge thereof, of means for supporting said top on said automobile comprising a post formed from sheet metal into a substantially trough-shaped section, the free edges of which are bent to form a T shaped slot in cross section lying within said trough-shaped section, the leg of the T opening on to the face thereof to receive and guide an edge of said enclosure and of less width than the thickness of said protuberances which have sliding engagement within the head of the T thereby to prevent disengagement of the edge of said enclosure and said slot.

Signed by me at Detroit, Michigan, U. S. A., this 31st day of October, 1924.

JOSEPH H. BOURGON.
